UNITED STATES PATENT OFFICE.

RUDOLF JAHODA, OF VIENNA, AUSTRIA-HUNGARY.

INCANDESCENT ELECTRIC LAMP.

1,063,035.

Specification of Letters Patent. Patented May 27, 1913.

Application filed December 23, 1911. Serial No. 667,454.

To all whom it may concern:

Be it known that I, RUDOLF JAHODA, subject of the Emperor of Austria-Hungary, residing at Vienna, Austria-Hungary, have 5 invented certain new and useful Improvements in Incandescent Electric Lamps, of which the following is a specification.

Heretofore the method of arranging metallic filaments of considerable length within 10 glow lamp bulbs consisted almost exclusively in winding the filament on a support formed essentially of two supporting spiders in such a manner that the filament is distributed around a cylindrical surface. The disadvantage of this arrangement is that the lamp 15 radiates very little light in a downward direction. Other arrangements have been proposed for the purpose of producing light radiation in a downward direction, but in these 20 cases the lateral radiation is reduced.

The present invention has for its object 25 to provide a lamp which will radiate light uniformly in all lateral directions as well as downwardly. This effect is obtained by the arrangement hereinafter described and shown in the accompanying drawing, in which—

Figure 1 is a perspective view, Fig. 2 a 30 plan view and Fig. 3 is a plan view of a modification.

a designates an axial supporting rod carrying on its upper and lower ends respectively two cross bars *b* and *c* preferably arranged at right angles to each other.

35 *d* and *d'* are the leading-in-wires. The cross bars *b* and *c* are formed with loops 1, 2, 3, 4, 5, 6, 7, 8 for the reception of the filament, which extends from *d'* over 1—8—2—7—3—6—4—5 to *d*. Thus the filament 40 is distributed over a warped surface and there is no position in which the individual sections of the filament cover each other, so that a highly efficient distribution of light is obtained.

45 In some cases it may be necessary to employ a filament of considerable length and in such cases the cross bars would have to be considerably extended. This inconvenience is avoided by the modified arrangement.

shown in Fig. 3, wherein the cross bars *b* and *c* are provided on each side with a longitudinal row of small hooks 1, 1' to 8, 8' for the reception of the filament, so that light will be emitted by two parallel warped surfaces. The filament will then run from 1 over 8, 2, 55 7, 3, 6, 4, 5, 5', 4', 6', 3', 7', 2', 8' to 1'. The section of the filament from 1 to 5 determines the exterior light emitting surface and the section from 5' to 1' determines the interior light emitting surface. 60

Claim.

1. An incandescent lamp comprising two filament supporting crossed members spaced apart, and a filament connected with said members at the same and at different relative positions from the centers of said members. 65

2. An incandescent lamp comprising an axial support, bars mounted thereon and crossing each other, and a filament extending from the outer end of one bar to the outer end of the other bar, and from the last named position to a point on the other bar intermediate its ends and center. 70

3. An incandescent lamp comprising an axial support, bars mounted thereon and crossing each other, and a filament extending from the outer end of one bar to the outer end of the other bar, and from the last named position to a point on the other bar 75 intermediate its ends and center and from said intermediate point to a corresponding point on the first named bar.

4. An incandescent lamp comprising a support, two filament supporting members 80 spaced apart along the support and crossing each other and a filament extending from one bar to the other in a plurality of windings inclined both to the bars and to the support. 85

In testimony whereof I have hereunto set my hand in presence of two subscribing witnesses.

RUDOLF JAHODA.
